UNITED STATES PATENT OFFICE.

ANDREW M. DEIG, OF SEATTLE, WASHINGTON.

DESIGN FOR A COMBINATION CHECKER-BOARD AND TRAY.

58,138.

Specification for Design.

Patented June 14, 1921.

Application filed February 14, 1921. Serial No. 445,009. Term of patent 7 years.

To all whom it may concern:

Be it known that I, ANDREW M. DEIG, a citizen of the United States, residing in Seattle, in the county of King and State of Washington, have invented a new, original, and ornamental Design for a Combination Checker-Board and Tray, of which the following is a specification, reference being had to the accompanying drawing, forming part thereof.

The figure is a perspective view of a combination checker-board and tray, showing my new design.

I claim:

The ornamental design for a combination checker-board and tray, substantially as shown.

ANDREW M. DEIG.
